UNITED STATES PATENT OFFICE

168,084

COMBINED FOOD AND BEVERAGE VENDING STATION

Louis A. Zon, Buffalo, N. Y.

Application August 12, 1952, Serial No. 20,986

Term of patent 14 years

(Cl. D13—1)

To all whom it may concern:

Be it known that I, Louis A. Zon, a citizen of the United States of America and residing at Buffalo, in the county of Erie and State of New York, have invented a new, original, and ornamental Design for a Combined Food and Beverage Vending Station, of which the following is a specification, reference being had to the accompanying drawings, forming part thereof.

Fig. 1 is an elevational view of the front of a combined food and beverage vending station, embodying my new design.

Fig. 2 is a side elevational view thereof, viewed from the right of the station as shown in Fig. 1, the left hand side being similar in appearance.

Fig. 3 is a top plan view thereof.

I claim:

The ornamental design for a combined food and beverage vending station, substantially as shown.

LOUIS A. ZON.
